UNITED STATES PATENT OFFICE.

EDWIN L. WHITE, OF BROOKLYN, NEW YORK.

COMBINED BOWL-HANGER AND SOCKET-SUPPORT.

1,270,904.

Specification of Letters Patent.

Patented July 2, 1918.

Application filed February 20, 1918. Serial No. 218,191.

To all whom it may concern:

Be it known that I, EDWIN L. WHITE, a citizen of the United States, residing at the borough of Brooklyn, in the county of 5 Kings, city and State of New York, have invented an Improvement in Combined Bowl-Hanger and Socket-Support, of which the following is a specification.

My invention relates primarily to lighting fixtures of the indirect lighting character, and particularly to means for supporting the bowls and sockets in such fixtures, in which the bowls are not drilled with holes for the attachment of the hangers or socket 10 supports, and it consists in providing a combined bowl hanger and socket support which may be clamped to bowls of various shapes and thickness with great facility.

In the accompanying drawing:

20 Figure 1 is a side elevation of my improved device complete.

Fig. 2 is a side elevation of the bowl hanger member.

25 Fig. 3 is a rear elevation of the socket supporting member.

Fig. 4 is a side elevation showing this device connected to a bowl, the latter being in section, and

30 Fig. 5 is a similar view showing a slight modification in the shape of hanger member and bowl.

Similar reference characters indicate like parts throughout the several figures.

10, indicates the bowl hanger member, and 35 11 the socket supporting member.

These members are each preferably formed from one piece of flat metal, and while they may be cast, I prefer that comparatively thin metal be employed and bent 40 to the desired shape so as to possess a certain degree of resiliency by which the strain upon the glassware will be lessened in the member contacting therewith.

The member 10, is of a shape to fit over 45 the rim of a bowl 12, while its inturned forward end 13, fits under the flange 14, of the bowl when the same is of a shape illustrated in Fig. 4, or where the bowl has only an out-turned lip as in Fig. 5, the end of 50 the hanger may be bent at a lesser angle and bear against the outer surface of the bowl as shown in such figure.

The other end of the member 10, is bent 55 downwardly a predetermined distance, and then upwardly, forming a recess 15, at this point, above which the metal is preferably

bent to form a hook 16, as shown in Figs. 1, 2 and 4, or it may extend upwardly in a straight or inclined direction with a hole bored near its upper end for the reception of a 60 hook or end link 18, of a chain 19, as shown in Fig. 5.

Alined threaded holes 20, are provided through the metal at both sides of the recess 15, for the reception of a binding 65 screw 21.

The member 11, has an enlargement 22, at its upper end, the center of which is cut out forming an opening 23, between which and the top edges there is a hole 24, which 70 may be threaded if desired, but this is not necessary, as it is preferably a smooth bore. The lower end of the member 11, is provided with a hollow exteriorly threaded stud 25, for the attachment of a lamp socket. 75

In assembling the parts, the hook 16, on the member 10, is passed through the opening 23 in the member 11, and the upper end of this member is then drawn down into the recess 15, bringing the hole 24, in register 80 with the threaded holes 20, in the member 10, after which the binding screw 21, is inserted, securely fastening the member 11, within said recess. The top of the opening 23, is preferably cut in a straight line which 85 seats upon the bottom of the recess 15, preventing any lateral movement of this member.

My invention provides a combined bowl hanger and socket support which may be 90 attached to or removed from bowls of various shapes and thickness with great facility. The screw 21, performs the double function of retaining the socket support in place, and clamping the combined device 95 to a bowl.

I claim as my invention:

1. A device of the character described, comprising a member formed from one piece of flat metal having a substantially horizontal portion adapted to rest upon the top surface of a bowl flange, its forward end being bent to conform to the outer edge of said flange and extend under the same, the rear end of said member being bent downwardly and then upwardly forming a recess and provided with alined threaded holes in said bends, the upper end of such portion being formed to receive a hook or link of a chain, another member formed of 110 a flat piece of metal provided at its lower end with a stud to receive a lamp socket,

- and having its upper end fitted within said recess in the other member and provided with a hole registering with said threaded holes in such member, and a screw passing through said holes by means of which said first member is clamped to the bowl and said second member held in position.
2. A device of the character described, comprising a member formed from one piece of flat metal having a horizontal portion adapted to rest upon the top surface of a bowl flange, its forward end being bent to conform to the outer edge of said flange and extend under the same, the rear end of said member being bent downwardly and then upwardly forming a recess and provided with alined threaded holes in said bends, the upper end of said portion being formed to receive a hook or link of a chain, another member formed of a flat piece of metal provided at its lower end with a stud to receive a lamp socket, and at its upper end with an opening through which the rear end of the first member may be passed, the top of said opening being cut in a straight line to seat upon the bottom of said recess, said second member being fitted within said recess and provided with a hole registering with said threaded holes in the first mem-
- ber, and a screw passing through said holes by means of which said first member is clamped to the bowl and said second member held in position.
3. In a lighting fixture, the combination of a bowl provided with a flange having a flat top and straight vertical outer edge, of a hanger formed of one piece of flat metal having a horizontal portion adapted to rest upon the top of said flange, its forward portion being bent to conform to the outer edge of the flange and extend under the same, its rear end being bent downwardly and then upwardly forming a recess and provided with alined threaded holes in said bends, a member formed of a flat piece of metal provided at its lower end with a stud to receive a lamp socket and having its upper end fitted within said recess in the hanger and provided with a hole registering with said threaded holes in said hanger, a screw passing through said holes by means of which said hanger is clamped to the bowl and said member held in position, and a supporting chain connected with said hanger.

Signed by me this 6th day of February, 1918.

EDWIN L. WHITE.
